SAFETY LOCK ELECTRICAL RECEPTACLE
AND PLUG THEREFOR

Charles H. Whitlock, El Dorado, Kans., assignor of one-eighth to Walter F. McGinnis, one-sixteenth to Henry C. Cox, one-sixteenth to Jack A. Webb, and one-sixteenth to Stewart Elton McCreight, all of El Dorado, Kans.; one-sixteenth to Harry Last and one-sixteenth to Dorothy Leon Last, Leon, Kans.; and one-sixteenth to Clyde C. Graham and one-sixteenth to P. A. Fouts, both of El Dorado, Kans.

Application May 24, 1948, Serial No. 28,845

4 Claims. (Cl. 173—330)

1

My invention relates to a safety lock receptacle and attachment plug.

An object of this invention is to provide an electrical convenience outlet and plug for use therein in which the plug cannot be pulled therefrom, as it can in the conventional type plug and receptacle.

Another object of this invention is to provide a device of the kind mentioned in which the contact points of the plug contact a large area of surface of the contact points of the receptacle thereby providing an electrical connection having a large capacity whereby there will be little or no voltage drops through the connection.

A still further object of the invention is to provide a device of the kind mentioned in which the several parts of the device are sturdy and well supported to insure long life and high efficiency of the device.

Another object of the invention is to provide a device of the kind mentioned in which the plug can be quickly and properly inserted in the receptacle.

Another object of the invention is to provide a device of the kind mentioned in which the ends of the wires of an extension cord will be automatically bent and pressed into permanent contact with the contact elements of the plug when the wires are placed in position in the plug and the parts of the plug are assembled.

Another object of the invention is to provide a device of the kind mentioned that is simple, neat in appearance, and one that is inexpensive to make and buy.

Now referring to the accompanying drawings in which similar numerals of reference designate the same parts throughout the several figures of the drawings; Fig. 1 is a side view of the plug.

Fig. 1—A is a fragmentary top plan view of the plug shown in Fig. 1.

Fig. 2 is a sectional view through the plug, the view being as seen from the line II—II in Fig. 1 and looking in the direction of the arrows.

Fig. 3 is a bottom plan view of the plug shown in Fig. 1.

Fig. 4 is a sectional view through a modified form of the plug, the view being as seen from the line IV—IV in Fig. 5 and looking in the direction of the arrows.

Fig. 5 is a bottom plan view of the modified form of the plug shown in Fig. 4, the lock and guide stem of the plug being removed for convenience of illustration.

Fig. 6 is a front face view of a duplex receptacle for receiving the above mentioned plug.

2

Fig. 7 is a sectional and side view of the plug receptacle, the view being as seen from the line VII—VII in Fig. 6 and looking in the direction of the arrows.

Fig. 8 is a sectional view through the plug receptacle, the view being as seen from the line VIII—VIII in Fig. 6 and looking in the direction of the arrows.

Fig. 9 is a perspective view of one of the receptacle contact elements, both contact elements in the receptacle being identical.

In the drawings is shown the receptacle device which comprises a block 10, the central portion of which is provided with a pair of parallel slots 11 and 11a. The block 10 is provided with a pair of contact elements A and B, that are identical and are constructed as shown in Figure 9. The contact points A and B comprise a strip 12 of metallic material and having downwardly turned leg elements 13 and 14, that are positioned, one on either side of the strip 12. The leg 13 is provided with a hole 15 to receive a screw 16. The outer ends of the strip 12 are bent into hook formations 17 and 18, each of which are directed in the same direction as shown in Fig. 9. These contact elements, as shown in Figure 9, when turned end for end form right and left contact points as will later be described.

30. The block 10 is provided with a pair of the contact elements shown in Figure 9 and the contact elements are placed one on top of, and one along the opposite edges of the block 10, to provide the contact elements A and B, shown in Figures 6, 7 and 8. In assembling the contact elements A and B on the block 10, the legs 14 of the contact elements A and B are positioned, one in each of the slots 11 and 11a of the block 10, and the legs 13 of the contact elements A and B are positioned, one against each of the opposite sides of the block 10. The block 10 is provided with a pair of indentures or holes 19 and 19a that are in registry with the holes 15 in the legs 13 of the contact elements A and B so as to receive the screws 16 that are threaded through the holes 15 for the purpose of wire connections to the contact elements A and B.

50. In the end portions of the block 10, and centered between the hook formation 17 of the contact element A and the hook formation 18 of the contact elements B is a hole 20 to receive a guide pin of an extension plug that will later be described.

On either end of the block 10 is shown outwardly extending ear-like elements 21 and 22 having screws 23 and 24 passed therethrough

and threaded into a face plate element 25 as a means of rigidly attaching the block 10 to the face plate 25.

The face plate 25 has two openings C and D therein that are circular in form and have oppositely extending notches 26 and 27 connecting therewith that are centered between the strips 12 of the contact elements A and B, and the circular portions of the openings C and D are concentric with the holes 20 in the block 10. The back side of the face plate 25 is provided with a pair of recessed portions 28 and 29 which extend from their respective notch 26 and 27 to the right to provide space for the hook elements 17 and 18 and also to provide space in which to turn the contact points of the extension plug to the right for contact and receiving purposes in the hook portions 17 and 18 of the contact elements A and B and to turn the extension plug to the left for disconnecting purposes as will readily be understood. The opposite ends of the face plate 25 is provided with screw holes H for the reception of screws to hold the device on the wall of a building or in a conventional conduit box.

While the block 10 is shown and described as being attached to the face plate 25 by means of screws 23 and 24 it is to be understood that the block 10 may be attached to the face plate 25 by any other suitable method such as cementing or fusing the parts together or even by integral connection at the time of manufacture.

The extension plug for use with the foregoing described convenience outlet receptacle comprises a body 30 that is preferably cone shaped and having an elliptical shaped base, although it is to be understood that the body 30 could be any other desired shape. The upper or apex end of the cone 30 is provided with an axially positioned opening 31 from which extend a pair of diverging holes 32 and 33 that end and open into a bore or opening 34 that is axially positioned in the opposite or other end of the body 30, the holes 32 and 33 being diametrically positioned to each other across the opening 34. A portion of the body 30 projects upwardly into the opening 31 in a V-shaped formation 10a, the sides of which slope forward and form a guide for the wires 35 and 36 into the holes 32 and 33.

Diametrically positioned across the opening 34 is a pair of metallic Z-shaped contact elements 37 and 38, the lower ends of which turn toward each other to form foot elements 37a and 38a and rest against the upper shoulder 39 of the opening 34. The legs of the Z-shaped contact elements are positioned in recesses formed in the body 30 and the side edges of the opposing feet 37a and 38a are provided with notches 37b and 38b that fit around the edges of the holes 32 and 33 for purposes that will later be described.

As shown in Figure 2 there is a retainer and binding plug 40 that is threaded into the opening 34 for the purpose of entering the contact elements 37 and 38 in their position and also for forcing contact of the wires 35 and 36 with their respective foot elements 37a and 38a as will later be described.

Between the holes 32 and 33 is positioned a bore 41 in the body 10 to slidably and revolvably receive a guide pin 42 that is integrally formed on the binding plug 40. The binding plug 40 is also provided with a multi-sided pin 43 that is an integral part of the plug 40 and extends in an opposite direction from the pin 42, the pins 42 and 43 being in axial alignment and also being positioned on the center axis of the plug 40.

The outer ends of the contact elements 37 and 38 are turned outwardly as at 37c and 38c to overlap a flange formation 44 that is an integral part of the body 10 and provides a space 45 between the contact points 37c and 38c and the bottom of the body 10.

In Figures 4 and 5 the plug is shown in a modified form of construction and the modification comprises a sleeve 46 that is pressed into the opening 34 as a definite retainer for the contact legs 37 and 38 in their recesses in the body 10 and the plug 40 is threaded into the sleeve 46 for the same purposes as above mentioned.

In assembling the wires 35 and 36 in the body 10 and connecting them with their respective foot elements 37a and 38a the insulation is moved from the ends thereof so as to expose a small portion or length of bare wire. The wires are then inserted, one through each hole 32 and 33 until the base ends of the wires project into the opening 34 and beyond their respective foot elements 37a and 38a, whereupon the binding plug 40 may be inserted and screwed into the opening 34 or sleeve 46 and as the plug 40 is turned in a right hand direction it will move toward the feet 37a and 38a and contact the ends of the wires 35 and 36 and bend the end of each wire 35 and 36 over its respective foot element 37a and 38a and as the plug 40 advances it will solidly mesh and press the ends of the wires 35 and 36 against their respective foot elements 37a and 38a to provide a good electrical contact there-between. In performing the above described operation, if desired, a wrench may be placed on the multisided pin 43 and the plug 40 further turned thereby to secure a more perfect contact of the wires 35 and 36 with their respective foot elements 37a and 38a.

In assembling the extension plug in the receptacle the pin 43 will be inserted in the hole 20 whereupon the contact points 37c and 38c will register with and pass through the opening extensions 26 and 27 whereupon the extension plug may then be turned in a right hand direction and the contact points 37c and 38c will move under the plate 25 and in the recesses 28 and 29 and enter into the hook portions 17 and 18 of the contact elements A and B. The extension plug may be removed from the receptacle in the reverse order from that with which it was assembled as above described.

It is obvious from the drawings and the foregoing description that the extension plug cannot be attached to, or detached from the receptacle by straight longitudinal movements of the plug relative to the receptacle, but those movements must also be supplemented by a rotary movement of the extension plug in order to contact and complete an electrical circuit so far as the extension plug is concerned. This arrangement always insures the extension plug of maintaining an electrical contact and prevents the extension plug from removal from the receptacle due to accidental pulls on the cord or wires 35 and 36.

While the foregoing description is that of attaching the plug to the receptacle for extension purposes it is also obvious that the plug may be entered into the receptacle and partially turned whereupon the plug will be held in the receptacle prior to the contact point of the plug coming into contact with those of the receptacle. In view of this it becomes obvious that the turning of the plug will serve the same purpose as a switch, and

this may be done without the removal of the plug from the receptacle.

While the device as shown in the drawings and herein described is probably the preferred form of the device, it is to be understood that such modifications of the device may be employed as lie within the scope of the appended claims without departing from the spirit and intention of the invention. Now having fully shown and described my invention, what I claim is:

1. In an electrical socket and extension plug device therefor; said plug having a body portion, said body portion having an axially aligned bore in each end thereof and the opposing ends of the said bores being spaced apart, said body portion having a plurality of openings connecting between said bores and positioned adjacent the outer edge of the said bores, a plurality of electrical contact elements, each of said elements having a post portion and a foot element thereon and having a hole in each foot element, said contact elements being positioned in a spaced apart position in one of said bores and having their foot elements bearing on the bottom of said bore and the hole in each foot element being in registry with an afore mentioned hole connecting between said bores, a retainer plug, said retainer plug being positioned in the bore containing the said electrical contact elements for holding the said electrical contact elements in a fixed position, and threaded means for moving said retainer plug toward the foot element of each of said electrical contact elements for the purpose of binding a wire end between each of said foot elements and the end of the retainer plug for electrical connection purposes.

2. In an electrical socket and extension plug device therefor; said plug having a body portion, said body portion having an axially aligned bore in each end thereof and the opposing ends of the said bores being spaced apart, said body portion having a plurality of openings connecting between said bores and positioned adjacent the outer edge of the said bores, a plurality of electrical contact elements, each of said electrical contact elements having a post portion and a foot element thereon and having a hole in each foot element, said contact elements being positioned in a spaced apart position in one of said bores and having their foot elements bearing on the bottom of said bore, and the hole in each foot element being in registry with an afore mentioned hole connecting between said bores, a retainer plug, said retainer plug being positioned in the bore containing the said electrical contact elements for holding the said electrical contact elements

in a fixed position, and threaded means for moving said retainer plug toward the foot element of each of said electrical contact elements for the purpose of binding a wire end between each of said foot elements and the end of the retainer plug for electrical connection purposes, and guide means on the retainer plug for guiding and centering the extension plug device in a receptacle therefor, said guide means having a wrench hold formation thereon by which the retainer plug and said threaded means may be turned for the purpose specified.

3. In an electrical socket and extension plug device therefor; the structure defined in claim 2, said structure being further characterized by the exposed ends of the said electrical contact elements being turned outwardly in radial directions relative to the entire circular assembly of the device.

4. In an electrical socket and extension plug device therefor; the structure defined in claim 2, said structure being further characterized by the exposed ends of the said electrical contact elements being turned outwardly in radial directions relative to the entire circular assembly of the device in combination with the foregoing defined electrical extension plug structure, a socket for receiving said electrical extension plug, said socket having a body portion and a detachably attached cover plate therefor, means in said body portion for receiving the guide element of the said plug, and hook contact elements, one for each contact element of the extension plug and carried by the said body portion of the said socket, and means in said cover plate for receiving the contact elements of the plug and permitting the turning of the exposed ends of the contact elements of the plug thereunder as a means of locking the plug in the receptacle prior to the engagement of the contact points of the plug with the contact points of the socket, said plug contact points being engageable with the contact points of the socket upon continued advance turning of the extension plug device.

CHARLES H. WHITLOCK.
